DIE-CASTING MACHINES

Eric Kellett and Leslie William Chambers, Birmingham, England, assignors to The Birmingham Small Arms Company Limited, Birmingham, England

Application February 20, 1956, Serial No. 566,481

Claims priority, application Great Britain
February 25, 1955

11 Claims. (Cl. 22—68)

This invention relates to die-casting machines of the oil "hydraulic" type, its main object being to expedite the operational cycle of such machines.

The basic cycle of any such machine comprises closing of the die, injection of molten metal, opening of the die (after a sufficient interval for solidification of the metal), and ejection of the casting (sometimes after severing it from the runner), the necessary co-axial movements being effected by the pressure of the oil in cylinders containing the pistons of "jacks" connected to the movable elements of the machine. Apart from the common source of power, such movements are independent, and are effected seriatim, so that the time for the cycle approximates to the total time taken for the individual movements in the cycle. It is customary for the machines to be provided with auxiliary "jacks" for more complicated dies (molds) and/or for withdrawing cores from the completed casting, and the necessary movements (at right-angles or oblique to the axis of the movements of the basic cycle or otherwise) are again independent and effected seriatim, with further addition to the time for the cycle. Electrical control is sometimes applied to enable the movements to follow each other progressively, e. g., in an automatic cycle initiated by the operator; but the seriatim order of the operations still results in a long cycle.

Thus, in a machine operating on the "cold chamber" system, i. e., with the operator himself ladling the metal into the machine, the operator initiates each automatic cycle as soon as he has ladled the metal into an orifice in front of the injection plunger. In machines operating on the "hot chamber" system, as is possible with low-melting metals and alloys, such as zinc and zinc alloys, a further "jack" is provided for forcing a quantity of metal from the melting pot into the path of the injection plunger, and the automatic cycle is initiated by operation of a button by the operator to effect metal injection, or to effect closing of the die, die-closing then resulting in actuation of a pressure-operated micro-switch to effect injection only when there is a full pressure lock on the closed dies. In both cases, the usual method of operation requires a long cycle from the time the metal begins to be injected, because of the seriatim operation of the subsequent individual movements after the metal has "frozen" in the die.

According to the present invention, a die-casting machine comprises jacks operable by oil under pressure and in operative connection with at least one movable part for carrying a die part, an injector, and an ejector, and provision for at least one further jack in association with such movable part, common controlling means for effecting the movements of all the jacks, and interconnecting control means to effect operating movements of at least two of the jacks that are simultaneous over at least part of the times occupied by such of the movements as take place after "freezing" of the metal in the die. Thus, two selected movements may be contemporaneous

throughout or may overlap in time. As a result, the time of the whole cycle is less than the total time of the several movements by the amount of complete or partial overlap of any two or more of the movements.

- 5 If, as is frequently the case, the casting calls for die parts movable otherwise than co-axially with the movable part carrying the main die part, or for cores to be withdrawn at right-angles or obliquely, or for the unscrewing of cores used in the formation of internal or 10 external threads, this bringing into use one or more of the further jacks for which provision is made, the movement of any or all of such parts may partly or wholly overlap the movements of the basic parts or of each other, to minimise the complete cycle.
- 15 It is usual in existing machines for the oil to be supplied from a hydraulic pump of a capacity sufficient for any single jack movement, e. g., the die-closing jack, or from an accumulator charged by a hydraulic pump and of a capacity to effect any single jack movement, the 20 pump continuing to charge the accumulator during inoperative periods of the cycle, so that in either case there is sufficient oil capacity for the movements to take place in succession. To meet the greater oil requirements of the simultaneous or overlapping movements of the machine according to the invention, an accumulator may 25 likewise be used with a main pump, but—alternatively or additionally to such accumulator—it is preferred to provide a second pump to meet the requirements. Such pump is preferably variable in speed to enable capacity 30 to be adjusted to the casting requirements of any individual article.

Driving the pump by a variable-speed device adjusted to the requirements of any particular cycle enables excessive heating of the oil in the hydraulic circuit to be 35 avoided as also may be assisted by using an oil cooler, or by diverting excess oil by an unloading device.

The interconnecting control is preferably electrical, or mainly so. Thus, a timing unit with a cam or contact arm driven through gearing by an electric motor and set 40 in operation on injection of the metal may be used to complete an electric circuit after a sufficient interval for "freezing" (solidification) of the metal, to initiate the opening of the die and possibly other movements, 45 particularly the very early withdrawal of a core, when a separate core is necessary, e. g., by operating one or more solenoid-controlled valves in the hydraulic circuit. Any one or more of the movements other than for core-withdrawal or die-opening may, however, be dependent 50 on and take their timing from the core-withdrawing and/or die-opening movements, which two movements may also be independent. Thus one or more micro-switches may be operated at any pre-determined part of that movement to initiate one or more other movements, 55 e. g., by operating solenoid-controlled valves.

The invention will now be described in greater detail with reference to the accompanying drawings, in which

Figures 1 and 2 are side and front elevations of a typical die-cast part requiring the use of a transverse core;

Figure 3 is a front elevation of a die-casting machine showing the location of the main controlling members and some of the associated electric switches;

Figure 4 is a hydraulic diagram, including solenoid-controlled valves;

Figure 5 is a section of the diagram of Figure 4, showing a modification of the hydraulic system;

Figure 6 is an electric diagram, including the solenoid-control for the valves that directly operate the main elements for the die-casting proper;

Figure 7 is a timing diagram, showing a comparison with a machine operating by seriatim movements after "freezing" of the metal; and

Figures 8, 9, and 10 are comparative diagrams of pump and accumulator connections, first of known machines, next of one form of machine according to the invention, and finally of a further form of machine according to the invention.

The article shown in Figures 1 and 2 has the portion *x* of its hollow interior formed by a projection from one main die part, but the transverse hollow portion *y* must be formed by a core capable of being retracted transversely to the axis of the portion *x*. Similarly if a portion such as *y* is oblique to the axis of *x*: the core must be retractile obliquely. If such a portion as *y* is threaded (externally or internally), the part serving to form the threads must not only be retractile, but also capable of rotation. A co-axial portion such as *x* may also be threaded, which again calls for a rotatable and retractile part for forming its threads. Simple retraction merely calls for simple connection of a core part to an operating "jack," but—as is well known—the movement of such a jack may be transformed into a rotation of a core part by the use of a rack-and-pinion. It is also well known that, when several parts are die-cast simultaneously in one die, several core parts may be operated together from a single "jack."

In Figure 3, A¹, B¹, C¹, D¹ on the control panel *L* at the right are associated with the respective solenoid-controlled valves for effecting operation of the die, injection of metal, ejection of the article, and operation of the core. A "firing button" *a* is pressed when molten metal has been ladled into the machine, and constitutes a main controlling means to initiate injection, and a foot-operated button *b* constitutes further control means to close the die after ejection of the article. Some of a number of micro-switches operated by the die-movement are indicated at *c* and others operated by the core-movement at *d*. The movable part of the die is indicated as *A* and the "jack" for the core as *D*. The reference letter *A* is used for the die-jack in Figure 4, which also shows the core-jack *D*, the injection-jack *B*, and the ejector-jack *C*, these two latter not being seen in Figure 3.

Related to *A*, *B*, *C*, and *D* are reference letters A¹ (together with A¹¹), B¹, C¹, D¹ which are used in Figures 4 and 6 to indicate the corresponding solenoid-controlled valves for these four main elements of the machine, in relation to the electrical controls—including the buttons *a* and *b*. These figures show that the two solenoid-controlled valves, A¹ and A¹¹, both simultaneously operated, are associated with the die-jack *A*, the valve A¹¹ providing the direct control of pressure fluid to the jack *A* and the valve A¹ effecting cushioning of the "close" movement of the jack.

A typical timing diagram is shown in Figure 7, in which the various points in the total time cycle, starting from 0, a time when the die *A* is closed, are shown by I, II, III, etc.

The operator ladles in molten metal up to point I. He then presses button *a* which through an "in" relay *e* energises the "in" solenoid *f* of valve B¹ to effect injection up to point II. Simultaneously, a process timer *g* is energised. This is motor-driven, and makes a complete revolution for each complete operating cycle. The timer controls the "freezing" period, which ceases at point III. At this point, the timer operates a switch *h* to energise the "out" solenoid *i* operating valve D¹ to start core withdrawal. This continues to point IV, when a micro-switch *j* attached to the core mechanism (i. e., one of those at "d" in Figure 3) energises the "opening" solenoids *k* of valves A¹ and A¹¹, the latter of which starts the die opening. The function of valve A¹ is described below with reference to Figure 4. At point V, the normally closed micro-switch *l* operated by the die is opened, to cut off the current from the solenoids *k*. The valve A¹¹ is a three-position valve such that when neither of its solenoids is energised the

valve returns itself to the neutral position, allowing the pressure oil to pass straight through to drain. The core *D* continues to withdraw to point VI, when a micro-switch *m* on it is closed, re-energising solenoids *k*, thus continuing the die opening. The core withdrawal continues to point VII and on the die at this position is a micro-switch *n*, energising the "out" solenoid *o* of the ejection valve C¹, thus ejecting the casting. The ejection cycle thus ends at point VIII.

The operator now presses foot-button *b* to energise the "in" solenoid *p* of valve D¹ and simultaneously the "close" solenoid *q* of valve A, the current passing through normally closed micro-switch *r*. At point VIII when the die *A* is fully open, a micro-switch *s* energises the "out" solenoid *t* to return the injector, and cuts out solenoid *f* and the timer *g*, the button *a* being released. At point IX, a micro-switch *u* on the die motion energises "return" solenoid *v* of the ejector to point X. The die closing meanwhile continues to point XI when the normally closed micro-switch *r* opens the circuit, allowing the valves A¹ and A¹¹ to return to neutral position. The core is still returning and a micro-switch *w* corresponding to position XII re-energises the "close" solenoid *q* to complete the cycle at point XIII, the solenoid *p* being cut out, and the button *b* released.

The time-scale in Figure 7 shows that the cycle takes just under 6 seconds from the start of pouring the metal, the shaded rectangles showing the operations performed as described above. The white rectangles show the equivalent operations as performed in the known type of machine, the same article requiring a time cycle of 9 seconds. The saving of time begins at point III, after which, according to the invention, overlapping of the movements of the die *A*, core *D*, and ejector *C* takes place, as also—from point IX—does overlapping of the closing movement of the die *A* and return movements of the core *D*, ejector *C* and injector *B*. The resultant saving is more than one-third of the known cycle, i. e., output is increased by more than 50%.

In Figure 4, the jacks *A*, *B*, *C*, *D* are shown in approximately correct related position (the movable die part, the core, the injector, and the ejector plate all being omitted for the sake of clarity) together with the hydraulic connections from two supply pumps and an accumulator, and the four valves A¹, B¹, C¹, D¹. Three further solenoid-controlled valves are also shown. To avoid undue multiplicity of reference characters, like parts of the different main valves are indicated by similar references P (or P¹, P²), R, S, T in each case, as appropriate.

Oil is drawn from a tank 1 (through a strainer 2) by a low-pressure, variable-speed, pump 3 and a high-pressure pump 4. The pump 3 delivers through a differential unloader valve 5 and a check valve 6, and the pump 4 through a relief valve 7. A pilot line 8 from the body of valve 7 to the base of valve 5 causes the low-pressure delivery to be returned to the tank 1 if the delivery of the high-pressure pump 4 is in excess of say 1500 lbs./sq. inch (with a maximum of say 2000 lbs./sq. inch). Both pumps 3, 4 deliver to a main line 9, which is connected through a check valve 10, line 11, restrictor valve 12 and hydraulically-controlled check valve 13 with an accumulator 14. By a valve 15, the accumulator 14 feeds a pressure switch 16, which operates a solenoid-controlled valve 17 (electric connections not shown) that is energised when the machine supply is switched on to control the valve 13 through line 18 so as to allow free flow through the valve 13 to the line 11 so long as the switch 16 keeps the solenoid of the valve 17 energised, say at an accumulator pressure exceeding 1600 lbs./sq. inch. Below that pressure, the valve 13 closes, to prevent flow from the accumulator.

To effect closing of the jack *A*, when the valve A¹ is energised, a further solenoid-controlled valve A¹¹ is simultaneously energised. Oil flows from the main line 9 through a restrictor valve 19 and a check valve 20 to the

valve A¹¹, from which it passes both to the valve A¹ (through a check valve 21) and to an inner cylinder 22 of the die jack A (through a line 23). From the valve A¹ oil flows by a line 24 to a valve 25 to open a pre-filler tank 26 to the rear cylinder 27 of the jack A, so that oil is sucked into 27 as the jack closes the die. By a trip (one of the switches c in Figure 3), the valve A¹ is reversed to close the valve 25 (by line 28), and to overcome a check valve 29 connecting the line 28 to a pressure switch 30, which keeps the solenoid of the valve A¹ energised to hold the valve in reversed position. At this time, a port 27a is uncovered to put the cylinder 22 into communication with the cylinder 27, so that oil is now directed to the cylinder 27 and the jack A moves at a slower speed. This cushions the closing of the jack A.

To open the die, the valve A¹¹ is reversed by solenoid-actuation, and oil flows through a check valve 130 to the valve A¹, which is simultaneously operated to re-open the valve 25 of the pre-filler tank 26. Oil also flows by line 31 to the forward cylinder 32 of the jack A. Oil is pushed from the rear cylinder 27 to the tank 26, and from the inner cylinder 22 through the valve A¹¹ to the tank 1.

To effect injection, oil from the main line 9 passes by a line 33 to port P¹ of valve E and by the check valve 10 and a line 34 to port P² of the valve E. In the valve E, either P¹ or P² is blocked, so that either P¹ communicates with a line 35 or P² with a line 36. The valve B¹ is energised by one of its solenoids and pilot oil from the main line 9 passes to the right-hand control end of the valve E, so that main pressure passes by the line 36 and a restrictor valve 37 to the end 38 of the injector jack B. Pilot oil also passes to the base of a valve 39 at a rate to operate valve 39 slightly in advance of valve E, and oil can pass freely through the valve 39, in either direction. This permits oil displaced from the other end 40 of the jack B to the end 38 through a check valve 41, and a very fast injection speed is obtained from the oil supply in the accumulator 14, through the lines 11 and 34. When the pressure in the end 38 of the jack B exceeds say 1350 lbs./sq. inch, the end 40 is unloaded through the valve E and an adjustable differential unloading valve 42, to which pilot oil is fed from the line 36.

To return the injector, the solenoid of valve B¹ is de-energised, and pilot oil passes from the line 9 through the valve to the left-hand controlling side of the valve E; valve 23 now prevents flow from the end 40 of the jack B to the end 38, and main oil passes through the line 35 to the end 40. The end 38 exhausts through the restrictor valve 37, the valve E, and the unloading valve 42. The valve 42 is pre-set to change over at say 1350 lbs./sq. inch.

To effect ejection, oil from the main line 9 passes to the valve C¹, which is energised for the oil to pass through a restrictor valve 43 to one side of the jack C (the other side of which exhausts through the valve C¹), and to a pressure switch 44, which keeps the valve C¹ energised to hold the jack C out after ejection has ended. Reversal of the valve C¹ effects return of the ejector.

To effect retraction of the core, oil from the main line 9 passes to the valve D¹, which is energised for the oil to pass to the underside of the jack D, oil exhausting from the upper side through a restrictor valve 45. Reversal of the valve D¹ passes oil to the upper side of the jack D through the valve 45.

The groups of switches c and d (Figure 3) may be adjusted for precise operation at any desired times in the cycle, as dictated by the size and shape of the article to be die-cast, and (in conjunction with the solenoids they control) they provide for any desired movement to be interrupted or changed in course. Thus, any desired interlocking of the interdependent controls of the system may be effected. Thus, in the case of a component with a screwed core, the following sequence may take place after the solidification period; the screwed core begins to withdraw continuously, after a brief interval (say 1/2-

second) die-opening commences, and after complete withdrawal of the screwed core, the ejector ram operates.

Although reference above has been largely to the injection of molten metal, similar provision may be made in machines for die-casting plastic materials.

Figure 8 shows, in very simplified form, the known use of a single pump with an accumulator, with no attempt to show control valves, or indeed reversal of operation of the four jacks A, B, C, D. Figure 9 shows in comparative manner one use of two pumps according to the invention, with the accumulator 14 available to supply oil to the die jack A and the injection jack B; and Figure 10 another use of two pumps, with the accumulator supplied by one pump only to operate the injection jack B, leaving the other pump to operate the jacks A, C, and D.

Figure 5 shows, in a hydraulic system generally similar to that of Figure 4, a separate pump 50 directly operating the core jack D and the ejection jack C, as well as contributing (through a check valve) to the operation of the injector jack B, a relief valve 52 being provided in advance of the valve 51.

A restrictor valve 53 acts as a variable by-pass for a pressure switch 54, which keeps the valve D¹ energised to hold the cores out after withdrawal. A restrictor valve 55 connects the line 9 to a pressure gauge 56 for checking line pressure.

What we claim is:

1. A die-casting machine comprising two movable parts for carrying die members, with one of those movable parts capable of a movement other than co-axially with the movement of the other, jacks operable by oil under pressure and in respective operative connection with said parts, electrically operated valves to control the supply of oil to the jacks, an electric switch adjustably disposed for operation by jack-affected movement of one of said parts to operate the valve supplying oil to the jack for the other of said parts, whereby both of the said parts may partake of their respective said movements simultaneously, control means to initiate the movement of the first mentioned of said parts by electric operation of the valve supplying oil to its jack, and an electric control system connected to said electrically operated valves and to said electric switch.

2. A die-casting machine comprising movable parts for carrying die members, with one of those movable parts capable of a movement other than co-axially with the movement of the other, and also an injector, jacks operable by oil under pressure and in respective operative connection with said movable parts and the injector, electrically operated valves to control the supply of oil to the jacks, an electric switch adjustably disposed for operation by jack-affected movement of one of said movable parts to operate the valve supplying oil to the jack for the other of said parts, control means to effect operation of the injector, and a timing device also operated by the control means, the timing device in turn initiating an opening jack-affected movement of the first of said movable parts by electric operation of the valve supplying oil to its jack, and the jack-affected movement of that first part in turn effecting a simultaneous opening movement of the other of said parts.

3. A die-casting machine as in claim 2, comprising also an ejector, an oil-operated jack for the ejector and an associated electrically operated valve, and a further electric switch adjustably disposed for operation by jack-affected movement of one of the said movable parts to open the valve for the ejector to effect ejection of a moulded article during the movement of said movable part.

4. A die-casting machine comprising movable parts for carrying die members, with one of those movable parts capable of a movement other than co-axially with the movement of the other, jacks operable by oil under pressure and in respective operative connection with said parts, electrically operated valves to control the supply of

oil to the jacks, control means to initiate a jack-affected movement of the first of those movable parts, an electric switch adjustably disposed for operation by movement of that part to operate the valve supplying oil to the jack for the other of said parts, and thus to effect a simultaneous jack-affected movement of the other of said parts, further control means to initiate a jack-affected return movement of one of said parts, and a further electric switch adjustably disposed for operation by such movement of that part to reverse the valve supplying oil to the jack for the other of said parts, and thus to effect a simultaneous return jack-affected movement of that other part.

5. A die-casting machine comprising movable parts for carrying die members, together with an injector and an ejector, jacks operable by oil under pressure and in respective operative connection with said parts, the injector, and the ejector, electrically operated valves to control the supply of oil to the jacks, control means to effect an injection operation of the injector, a timing device also operated by the control means, the timing device in turn initiating a jack-affected opening movement of one of said movable parts by electric operation of the valve supplying oil to its jack, electric switches adjustably disposed for operation by and during the said opening movement of that part to operate the valve supplying oil to the jacks for the other said movable part and for the ejector, thus effecting a simultaneous jack-affected opening movement of the other of said parts and a jack-affected ejection movement of the ejector, further control means to initiate a jack-affected return movement of one of said movable parts, and further electric switches adjustably disposed for operation by and during the return movement of that part to reverse the valves supplying oil to the jacks for the other of said parts and the injector and the ejector, thus effecting simultaneous jack-affected return movements of both movable parts and of the injector and the ejector.

6. A die-casting machine comprising a movable part for carrying a die member, and a core member movable at an angle to the direction of the movement of the said movable part, jacks operable by oil under pressure and in respective operative connection with the movable part and the core member, electrically operated valves to control the supply of oil to the jacks, an electric switch adjustably disposed for operation by jack-affected movement of one of said parts to operate the valve supplying oil to the jack for the other of said parts, whereby both parts may partake simultaneously of their respective jack-affected movements at an angle to one another, and control means to initiate the movement of the first of said parts by electric operation of the valve supplying oil to its jack.

7. A die-casting machine comprising a movable part for carrying a die member, and a core member movable at an angle to the direction of movement of the said movable part, jacks operable by oil under pressure and in respective operative connection with the movable part and the core member, electrically operated valves to control the supply of oil to the jacks, control means to initiate a jack-affected movement of one of the two parts, electric switches adjustably disposed for operation by and during jack-affected movements of the two parts to operate the valves supplying oil to the jacks, so that either one of the two parts may control the movement of the other part, further control means to initiate a jack-affected return movement of one of said parts, a further electric switch adjustably disposed for operation by such movement of that part to reverse the valve supplying oil to the jack for the other of said parts, and thus to effect a simultaneous jack-affected return movement of that other part, and further electric switches adjustably disposed for operation by and during such return movements to operate the valves supplying oil to

the jacks, so as to control the return movement of the parts.

8. A die-casting machine comprising movable parts for carrying die members, including a core member, together with an injector and an ejector, jacks operable by oil under pressure and in respective operative connection with said parts and with the injector and the ejector, electrically operated valves to control the supply of oil to the jacks, control means to effect an injection operation of the injector by its jack, a timing device also operated by the control means, the timing device in turn initiating an opening jack-affected movement of the core member by electric operation of the valve supplying oil to its jack, electric switches adjustably disposed for operation by and during the opening jack-affected movement of that part to operate the valves supplying oil to the jacks for another of the movable parts and for the ejector, thus effecting a simultaneous opening movement of that other part and an ejection movement of the ejector, both by their jacks, further control means to initiate a jack-affected return movement of one of the movable parts and the core member, and further electric switches adjustably disposed for operation by and during the return movements of those parts to reverse the valves supplying oil to the jacks to control simultaneous jack-affected movements of the parts and of the injector and the ejector.

9. A die-casting machine comprising movable parts for carrying die members, together with an injector and an ejector, jacks operable by oil under pressure and in respective operative connection with said parts and with the injector and the ejector, electrically operated valves to control the supply of oil to the jacks, at least one pump to supply pressure-oil and an accumulator connected to such supply, the accumulator serving to supply oil for an injection movement of the injector jack, control means to operate one of the valves to effect such injection movement, a timing device also operated by the control means, the timing device in turn operating another of the valves to initiate a jack-affected opening movement of one of the movable parts, electric switches adjustably disposed for operation by and during movements of the movable parts to operate the valves so as to effect and control jack-affected opening movements of the parts and of the ejector, and in turn their jack-affected return movements and that of the injector, and further control means to initiate the return movements, the switch operation providing for overlap of the opening movements and in turn of the return movements by control of valves supplying oil to the jacks direct from the pumped supply.

10. A die-casting machine as in claim 9, wherein two pumps are provided, conduits and valving connecting one of said pumps with certain of said jacks for effecting opening and return movements thereof, conduits and valving connecting the other of said pumps with the accumulator, means connecting said other pump with certain of said jacks for effecting the opening and return movements not accomplished by said first named pump, with the exception of the injection movement of the said injector, and means connecting said accumulator with the injector jack to accomplish the last named injection movement.

11. A die-casting machine as in claim 9, wherein two pumps are provided and means connecting one of said pumps with the injector jack and with a jack for a movable part adapted to carry a core for effecting opening and return movements of said jacks, and means connecting the other pump to a jack for moving a main die part to effect opening and return movements thereof.
